UNITED STATES PATENT OFFICE.

JAMES H. WHITNEY, OF BROOKLYN, NEW YORK.

DESIGN FOR A SEWING-MACHINE TABLE.

SPECIFICATION forming part of Design No. 13,855, dated April 10, 1883.

Application filed December 5, 1882. Term of patent 14 years.

To all whom it may concern:

Be it known that I, JAMES H. WHITNEY, a citizen of the United States, and a resident of Brooklyn, in the county of Kings and State of New York, have invented a new and original Design for Sewing-Machine Stands, of which the following is a specification.

My design is fully illustrated in the accompanying drawings, to which reference is made, 10 and in which Figure 1 represents an end elevation, and Fig. 2 a side elevation, of a sewing-machine stand designed according to my present invention.

The leading feature of my design consists in 15 the two letters A and V having straight legs or edges, and composed to form the entire end frame of a sewing-machine stand. Thus each of the two end frames is formed of the letter V crossing the letter A, and the horizontal 20 stroke B of the letter A crossing and projecting with its ends laterally beyond the said letter A at the same place where it is joined by the letter V. The legs of each of the said two letters A and V are formed of straight bars, 25 as shown in the drawings. The flanges *a*, by which the frames are bolted to the top of the sewing-machine table, are formed upon the inside of the upper ends of the letter V, and the rollers *b* at the lower end of the frame are pivoted to lugs attached to the lower ends of the letter A, which form the feet of the stand. 30 The brace C between the two end frames is also formed by the letter A, the top and ends of which have flanges, by which it is bolted to the table-top and the end frames, respectively, 35 as shown in Fig. 2. It will be seen that the horizontal stroke B in Fig. 1 incidentally divides the crossed letters A and V of the end frame in such a manner that the portion above 40 the said stroke B represents the letter W, and the portion below the stroke represents the same letter inverted. On the outside of the frame and brace the letters of which they are

composed have plain beads *c* along their edges, the surface *d* between the said beads being 45 sunk, and may be ornamented by checks or flowers, or in any other suitable design. The beads *c*, while adding to the beauty of the design, serve as strengthening-webs to increase the rigidity of the frame. 50

I am aware that monograms of persons' names or initials have been wrought or cast in some portions of the frame of sewing-machines in a manner similar to that long in vogue of working or affixing them as distinguishing 55 marks of the owners or makers upon cloth, knives, swords, and a great number of articles; but I am not aware of the whole frame, as such, having been formed or composed entirely of the said two letters. 60

Having thus described my invention, I claim as new and desire to secure by Letters Patent—

1. The design herein shown and described, consisting of the two letters A and V, having straight legs or edges and composed to form 65 the entire end frame of a sewing-machine stand.

2. The design for a sewing-machine stand, consisting of two straight-legged letters A and V, crossing each other and joined by the horizontal stroke B, both ends of the said stroke 70 projecting laterally beyond the junction of the said letters A and V, and the said letters and stroke having beads *c* along their edges and a sunk surface between the said beads.

3. The design for a sewing-machine stand, 75 consisting of the letter A, forming the brace between the end frames and top.

In testimony that I claim the foregoing as my invention I have signed my name, in presence of two witnesses, this 1st day of December, 1882. 80

JAMES H. WHITNEY.
